(57) **CLAIM**

The ornamental design for a downwardly pivoting armrest, as shown and described.

DESCRIPTION

FIG. 1 is a perspective view of a downwardly pivoting armrest showing my new design.

FIG. 2 is a left side elevation view thereof.

FIG. 3 is a front elevation view thereof; and,
FIG. 4 is a top plan view thereof.

The broken lines are for illustrative purposes only and form no part of the claimed design.
